(57) **CLAIM**

The ornamental design for a bank of gaming machines, as shown and described.

DESCRIPTION

FIG. 1 is a front perspective view of a bank of gaming machines showing our new design in a first position; FIG. 2 is a front perspective view thereof in a second position;

FIG. 3 is a front perspective view thereof in a third position; FIG. 4 is a front perspective view thereof in a fourth position;

FIG. 5 is a front perspective view thereof in a fifth position; FIG. 6 is a rear perspective view thereof in the first position; FIG. 7 is a rear perspective view thereof in the second position;

FIG. 8 is a rear perspective view thereof in the third position; FIG. 9 is a rear perspective view thereof in the fourth position;

FIG. 10 is a rear perspective view thereof in the fifth position;

FIG. 11 is a front perspective view of the bank of gaming machines showing our new design in an alternative first position;

FIG. 12 is a front perspective view thereof in an alternative second position;

FIG. 13 is a front perspective view thereof in an alternative third position;

FIG. 14 is a front perspective view thereof in an alternative fourth position;

FIG. 15 is a front perspective view thereof in an alternative fifth position;

(Continued)

FIG. 16 is a rear perspective view thereof in the alternative first position;
 FIG. 17 is a rear perspective view thereof in the alternative second position;
 FIG. 18 is a rear perspective view thereof in the alternative third position;
 FIG. 19 is a rear perspective view thereof in the alternative fourth position; and,
 FIG. 20 is a rear perspective view thereof in the alternative fifth position.
 The dashed broken lines in the drawings illustrate portions of the bank of gaming machines that form no part of the claimed design.
 The appearance of the design sequentially transitions between the positions shown in FIGS. 1-5 and 6-10, and 11-15 and 16-20, respectively. The process or period in which one position transitions into another position forms no part of the claimed design.
